UNITED STATES PATENT OFFICE

91,120

DESIGN FOR AN IRONING MACHINE CABINET

Jabez C. Nelson, Syracuse, N. Y., assignor to Easy
Washing Machine Corporation, Syracuse, N. Y., a corporation of Delaware

Application September 22, 1933. Serial No. 49,320

Term of patent 14 years

To whom it may concern:

Be it known that I, JABEZ C. NELSON, a citizen of the United States, residing in the city of Syracuse, in the county of Onondaga and State of New York, have invented a new, original, and ornamental Design for an Ironing Machine Cabinet, of which the following is a specification, reference being had to the accompanying drawing forming part thereof.

Fig. 1 is a perspective view of an ironing machine cabinet showing my new design; and

Fig. 2 is another perspective view with an end leaf extended.

I claim:

The ornamental design for an ironing machine cabinet substantially as shown and described.

JABEZ C. NELSON.
